UNITED STATES PATENT OFFICE

WILLIAM A. GRISWOLD, OF NASHVILLE, TENNESSEE

COMBINATION RADIANT AND CIRCULATING GAS HEATER

Application filed September 4, 1930. Serial No. 479,633.

My invention relates to heaters in which the fuel is gas, either natural or artificial, and the important object of this invention is to provide a heater which is of compact and simple construction and economically manufactured, and in which part of the fuel burned is used for heating air traveling through flues to be discharged into the room, and in which some of the fuel is used for heating radiant units or mantles from which the heat is projected directly by radiant energy into the room.

A further object is to provide a front row of gas ports for supplying the radiant mantles vertically arranged along the front of the stove, and a rear row of ports for supplying the heat for the air circulatory flues.

Another object is to provide a unitary burner having a front row of gas ports and an inner row of gas ports, and simplified and improved means for quickly installing the burner and holding it securely in position.

The above referred to important features, and other features of my invention, are incorporated in the structure disclosed on the drawings, in which drawings:

Figure 1 is a perspective elevation of the heater with the outer casing removed, and parts of the stove structure broken away to more clearly disclose the arrangement and operation.

Figure 2 is an enlarged vertical section of the heater on plane II--II of Figure 1;

Figure 3 is an enlarged section on line III--III on Figure 2;

Figure 4 is an enlarged plan view of one end of the burner and the surrounding supporting framework;

Figure 5 is a front elevation of one end of the burner with the supporting framework in section;

Figure 6 is a section to reduced scale taken on plane VI--VI of Figure 2.

The heater shown comprises an outer or ornamental casing or enclosure, and the inner heating structure surrounded and enclosed by the outer ornamental casing. The outer casing comprises a base structure 10 mounted on legs 11. The ornamental front 12 is supported on the base along the front

edge thereof while the rear wall 13 and the side walls 14 are mounted along the rear and side edges of the base, these walls and the front 12 being surmounted by the ornamental top 15 having the passageways 16 for the outflow of heated air into the room which is to be heated. The base structure, the front 12, and the top 15 may be in the form of castings and the rear and side walls may be in the form of sheet metal panels, all suitably 60 ornamented by enameling or otherwise.

The inner or heating structure comprises a bed plate or base 17 which is supported by lugs 18 extending from the base 10 of the outer casing. Inwardly a distance from its rear edge this bed plate 17 supports a row of vertical flue structures 19, of which there may be any number, three being shown. Each flue has longitudinally extending baffle and distributor ribs 20 extending there-through and seats on the bed plate 17 over an air inlet opening 21, so that air may flow upwardly through the flues to be heated.

The flue units are surrounded by an enclosure structure comprising a rear wall 22, side walls 23 and 24, a top wall 25, and a front wall 26, the rear and side walls extending between the bed plate 17 and the top wall 25 but the front wall 26 extends downwardly from the top wall and terminating a distance above the bed plate and is provided with a forward deflection 27 forming a hood or canopy. The rear and side walls are secured at their lower ends in any suitable manner to the bed plate 17 and at their upper ends are secured to the top plate 25, while the front wall 26 is secured to the side walls. The top plate has the openings 28 surrounded by depending flanges 29 which interlock with the flanged ends 30 of the flue units so that these flue units will be accurately aligned.

The flue units are spaced forwardly a distance away from the rear wall 22 and the units are also spaced apart laterally and from the side walls 23 and 24. A distance downwardly from its upper end each flue unit is encompassed by a horizontal flange or web 31, these webs being in a common horizontal plane and abutting each other between the 100

units, the flue flanges along the rear edge abutting and registering with the forwardly extending horizontal flange or fin 32 on the rear wall 22, while the outer flange sections 5 on the units abut against and are in registration with the webs 33 extending inwardly from the side walls 23 and 24. These flanges or webs on the rear and side walls and on the flue units form a continuous horizontal 10 diverting or baffling partition.

The space above this partition and between the rear and side walls 22, 23, and 24, and the top plate 25, is connected with the outlet 15 35 adapted for connection with a suitable outlet flue or chimney. The rear wall 13 of the outer casing is provided with the opening 36 for the passage of the stove pipe leading from the outlet 35.

A distance above the lower ends of the 20 flue units each unit is encompassed by a flange 37 and these flanges between the units abut laterally against each other and at the outer sides of the end units the flanges abut against 25 and align with the webs 38 extending inwardly from the side walls 23 and 24. The flanges together with the webs 38 form a horizontal partition which, however, does not extend entirely to the rear wall 22 but is separated therefrom by the passageway 39.

30 On the flue units are the vertical webs extending along the sides thereof for a distance upwardly from the flanges 37 and between units these flanges abut against each other and on the end units the flanges abut against 35 the vertical webs 41 on the adjacent side walls 23 and 24, the flanges 40 and the webs 41 forming a vertical partition above the flanges 37 for baffling the flow of the combustion products transversely of the units. The 40 spaces 42 between the flanges 40 and the horizontal flanges 31 are open for the transverse passage of combustion products and likewise the spaces 43 between the horizontal flanges 31 and the top plate 25 are open for the transverse flow of the combustion products.

45 Substantially in alignment with the flanges 37 on the two units is the horizontally extending baffle plate 44 which rests on the front sections of these flanges and is secured 50 at its end to the side walls 23 and 24 as by means of bolts 45. This plate forms a continuation of the baffle wall formed by the flanges 37 and webs 38 and has holes 44' therethrough which, as will be explained later, 55 permit direct upward flow of some of the products of combustion.

60 Substantially in alignment with the upper edges of the vertical flanges 40 is the plate 46 which rests between lugs 47 and 48 on the units and which is secured at its end to the side walls 23 and 24 as by means of bolts 49. This plate has forwardly and downwardly extending fingers 50 which cooperate 65 with the baffle plate 44 to support and align the radiant units or mantles 51.

Describing now the burner structure and arrangement, the burner body 52 is rectangular and has the front and rear ridges 53 and 54 provided respectively with the gas outlet ports 55 and 56. The burner body has the 70 supply pipe 57 extending downwardly and laterally therefrom for connection with a gas supply main in the usual manner at one end of the heater structure. Secured to this pipe and to lugs 58 on the burner body is a 75 plate or tray 59.

The burner body is positioned within the opening 60 in the bed plate 17 along the front of the flue units and the side walls 22 and 23 extend forwardly along the sides of this 80 opening. The burner body is inserted through the opening from the bottom thereof and on its side has fins 61 and 62 each provided with a notch 63, which notches receive the supporting fingers or lugs 64 extending from the bed plate 17 adjacent the front and rear edges of the opening 60, and after the burner has been inserted vertically it is shifted laterally to carry the notches 63 away from the lugs and to bring the fins 61 and 62 85 above the lugs so that the burner will then be supported vertically. After such lateral shifting of the burner to support it on the lugs, a wedge member 65 is inserted between one end of the burner body and the adjacent 90 edge of the opening 60 so as to lock the burner against longitudinal displacement, as clearly shown in Figures 4 and 5. When the burner is in position, the tray 59 will register with the opening 60 but will be displaced 95 a distance below the bed plate 17 for the passage of air to the burner. Additional openings 66 are provided in the bed plate in front of the burner for the flow of air.

100 The ornamental front 12 for the outer casing has the sill 67 which along its inner end provides the horizontal shelf 68 for supporting the radiant units or mantles 51. These units are of porcelain or other ceramic material and are tubular and of rectangular 105 cross section. As shown in Figure 1, their front walls are of scroll or grill formation and the front and rear walls have the baffle points or projections 69. The units are open 110 at their lower ends and rest with their front edges on the ledge 68 and are held thereon by pins 70 projecting from the ledge. The upper ends of the units are closed and flanges 71 115 extend upwardly therefrom to abut against the rear sides of the fingers 50 on the plate 46, 120 the units resting with their back walls against the front edge of the baffle plate 44, the units being thus accurately held in alignment and being placed side to side to form a continuous wall. At their lower ends, the 125 aligned units are above the ports 55 in the front ridge 53 of the burner so that the frame from these ports will project into the units and heat them, and particularly the points 69, to incandescence, and this heat is radiated 130

forwardly from the stove through the opening in the ornamental front 12. The products of combustion may flow from these units through holes 71' provided in the back walls of the units near the upper ends thereof. 5 These products of combustion will flow upwardly and through the passages 42 and 43 between the flue units into the space 34 from which they escape through the outlet 35 and through the stack or chimney.

10 To protect the radiant unit or mantle and to keep persons from coming in contact therewith, bars 72 are extended in front thereof between the side walls of the ornamental front 12, as shown in Figures 1 and 6. These bars are detachably applied in suitable openings 73 and at one end each bar has a lug 74 for engaging behind the corresponding wall so that the bars are thus locked against horizontal displacement after having been applied. It will be noted that the rear row of gas ports 56 is behind the wall of mantles so that practically all of the heat furnished by the burning of the gas at these ports is utilized in heating the flues through which air travels for delivery into the room from the top of the heater. The gas issuing from the front row of ports 55 is utilized in greater parts in heating the mantles for the radiant discharge of heat into the room.

15 The outer ornamental casing is spaced away at the rear and sides from the inner or heating structure and these spaces are open at the bottom with the space below the heater through openings 75 in the bed plate 17 and at their upper ends these spaces are open to the atmosphere through the passages 16 in the top or cover plate 15.

20 The operation of the heater is as follows:

25 The products of combustion from the rear row of gas ports are drawn rearwardly by the chimney draft and flow through the spaces between the flue units below the baffle wall formed by the unit flanges 37 and webs 38, the products flowing upwardly through the passage 39 behind the vertical baffle wall formed by the flanges 40 and webs 41, and then forwardly through the passages 42 below the baffle wall formed by the flanges 31 and the webs 32, and the products then flow rearwardly through the passages 43 and into the space 34 and out of the stack. The products of combustion take thus a circuitous path around and about the flues and heat the air traveling upwardly through the flues, which air is delivered from the top of the heater into the room to be heated.

30 The gas from the front row of gas ports 55 is utilized in greater part in heating the radiant units or mantles to incandescence and the heat is radiated from these mantles forwardly and into the room. The products of combustion escape through the openings 71' in the mantles and upwardly through the 35 passageways 43 into the space 34 and to the

stack. Some of the products of combustion from the rear row of ports, which escape the pull of the draft, will flow upwardly through the holes 46 in the baffle plate 44 and then through the spaces between the fingers 50 and then through the passageways 43 and to the stack. Air also flows upwardly through the openings 75 and through the space between the outer casing and the inner stove structure and is heated and flows into the room 40 through the openings 16 in the top 15.

45 My improved heater has all the advantages and efficiency of a radiant fire heater and besides functions efficiently as a circulating gas heater, the room being rapidly heated by the radiant discharge of heat forwardly of the heater and towards the lower part of the room, and by the hot air flowing out of the top of the flues. The various parts, particularly the burner structure, are 50 designed so that they may be readily and quickly assembled or dismantled.

55 Modifications and changes in the structure, arrangement and operation may be made without departing from the scope and 55 spirit of the invention, and I do not, therefore, desire to be limited to the precise structure shown.

I claim as follows:

1. In a heating structure of the class described, the combination of a stove body, flue structures within said body having vertical passageways therethrough for the upward flow of air to be heated, a single burner structure at the bottom of said stove body having 95 a rear row of gas outlet ports, means for deflecting around and through said flue structure the products of combustion resulting from the burning of gas at said ports, said burner having a front row of gas ports, and 100 upright radiant elements mounted in a row above said front row of ports to receive gas only from said ports and to be heated by the burning of the gas at said ports and to radiate the heat forwardly to the exterior of said 105 heating structure.

2. In a heating structure of the class described, the combination of a stove body, a flue structure within said body having vertical passageways for the flow of air to be heated, a rear row of gas ports for burning gas for heating said flue structure and the air flowing therethrough, a row of radiant units in front of the lower part of said flue structure forming a vertical baffle wall in front of 115 said rear gas ports for restricting the products of combustion from said ports to flow toward said flue structure, and an independent row of gas ports for delivering gas into said 120 units for the heating thereof, the heat being 125 radiated from said radiant units forwardly from the front of the heater structure.

3. In a gas heating structure, the combination of a supporting base, walls mounted on said base forming an enclosure, flue struc- 130

ture within said enclosure having vertical passageways for the flow of air to be heated, an opening in said base in front of said flue structure, a burner structure adapted to be projected upwardly through said opening, wings on said burner structure having notches, lugs on said base for registering with said notches whereby when said burner is projected through said opening said notches will permit vertical passage of said wings past said lugs and longitudinal shift of the burner structure will then carry said wings in position to rest on said lugs, and means for locking said burner structure 15 against longitudinal displacement.

4. In a gas heating structure, the combination of a supporting base, walls mounted on said base forming an enclosure, flue structure within said enclosure having vertical passageways for the flow of air to be heated, an opening in said base in front of said flue structure, a burner structure adapted to be projected upwardly through said opening, wings on said burner structure having notches, lugs on said base for registering with said notches whereby when said burner is projected through said opening said notches will permit vertical passage of said wings past said lugs and longitudinal shift of the burner structure will then carry said wings in position to rest on said lugs, and a wedge member inserted in said opening between one end thereof and the adjacent end of said burner structure for locking said burner structure against longitudinal displacement 35 after application thereof on said lugs.

5. In a gas heating structure of the class described, the combination of a supporting base, walls supported on said base forming an enclosure, flue structure within said enclosure having passageways for the flow of air to be heated, said base having an opening extending along the front of said flue structure, a burner structure adapted to be projected upwardly through said opening, means operable during longitudinal shift of said burner structure within said opening for locking said burner structure against vertical displacement, and wedge mechanism for locking said burner structure against longitudinal displacement.

6. In a heater structure of the class described, a combination of a supporting base, walls mounted on said base forming an enclosure, flue units mounted within said enclosure and having vertical passageways for the flow of air to be heated, a burner at the lower part of said enclosure, said burner having a rear row of gas ports for the combustion of gas for heating said flues, said burner having a front row of gas ports, a row of radiant units mounted above said front row of ports to receive gas therefrom and to be heated thereby, a horizontal baffle wall structure above the rear row of ports, said radiant

units resting with their backs against the front edge of said baffle wall, and a row of fingers above said baffle wall engaging against the front of said radiant units, said fingers and said baffle wall holding said radiant units 70 in alignment, and an ornamental outer casing surrounding said enclosure and having an opening through which said radiant units are exposed for the radiation of the heat from said radiant units. 75

7. A combination radiant and circulating gas heater comprising an enclosing frame having an opening in its front wall, a radiant fire structure forming a vertical wall across the inner end of said opening, a row 80 of gas outlets below said radiant fire structure for supplying gas for combustion therein and for the projection of radiant heat outwardly through said opening, a vertical flue structure within said enclosing frame behind said radiant fire structure having a passageway for the upward flow of air to the exterior of said frame at the top thereof, a stack outlet at the upper end of said frame, a row of burner outlets at the bottom of said frame between said flue structure and said radiant heat structure whereby the products of combustion from the gas burned in said outlets will flow around said flue structure and through said stack outlet to heat the air 90 flowing through said flue structure, said radiant fire structure isolating said products of combustion from said radiant heat outlet opening in front of said radiant fire structure, and a hood formed on said frame above 95 said opening for receiving the fumes and products of combustion from said radiant fire structure and directing them to said stack outlet.

8. A combination radiant and circulating gas heater comprising an enclosing housing having a front opening at the lower part thereof for the escape of radiant heat, a vertical wall of radiant units closing the inner end of said radiant heat outlet, a vertical flue element within said housing behind said radiant heat wall for the upward flow of air to the exterior of the housing at the top thereof, means providing a tortuous path around said flue structure, the space behind said radiant heat wall communicating with said path at the lower end thereof and a stack outlet from said housing connected with the upper end of said path, a burner structure at the bottom of said housing having a front row of gas outlets for feeding gas into said radiant heat units for burning therein, said burner structure having a rear row of gas outlets for gas to be consumed in the space behind said radiant heat wall, said wall forming a baffle for directing the products of combustion from the space behind said wall into said path for upward flow through said path and out of the stack outlet, said wall isolating said products of combustion from said radi- 130

ant heat outlet, and a hood on said housing overhanging said radiant heat outlet and for receiving and directing the fumes and products of combustion from said radiant heat units to said stack outlet.

9. A combination radiant and circulating gas heater comprising an enclosing housing having a front outlet along its lower part for the outflow of radiant heat, a radiant fire structure forming a vertical wall closing the inner end of said outlet, a flue structure within said housing behind said wall, means forming a tortuous path around said flue for the flow of products of combustion, there being an air passageway through said flue for the passage of heated air to the exterior of said housing at the top thereof, the space behind said wall communicating with said path at its lower end and a stack outlet connected with the upper end of said path, a burner structure at the bottom of said housing having a front row of gas outlets for feeding gas to the interior of said radiant fire structure and having a rear row of gas outlets for supplying gas to the space behind said wall, a baffle between said wall and said flue structure cooperating with said wall to direct the products of combustion from said rear row of gas outlets into the lower end of said path and for isolating said products of combustion from said radiant heat outlet, and a hood overhanging said radiant heat outlet for receiving the fumes and products of combustion from said radiant fire structure and conducting them to said stack outlet.

10. In a gas heating structure of the class described, the combination of a supporting base, an enclosure mounted on said base, heating elements within said enclosure, said base having an opening, a burner structure adapted to be projected upwardly through said opening, means operable during longitudinal shift of said burner structure within said opening for locking said burner structure against vertical displacement, and means for locking said burner structure against longitudinal displacement.

11. In a combination radiant and circulating gas heater, the combination of a housing having a front opening at the lower part thereof, a vertical wall of radiant units extending across said opening for direct exposure to the exterior of the housing, means defining an air passageway through said housing for the upward flow of air to the exterior of the housing at the top thereof, a stack outlet near the top of the housing, means defining a combustion passageway from the lower part of said housing to said stack outlet and in intimate association with said air passageway for heating the air flowing therethrough, a set of burner outlets underlying said radiant units for supplying gas thereto for combustion therein, and a second

set of burner outlets at the lower part of said combustion passageway.

12. A radiant and circulating gas heater comprising a housing having a front opening at the lower part thereof, longitudinally extending radiant units positioned across the front opening and normally exposed to direct heat exteriorally of said housing, front and rear rows of gas burner outlets in said housing, flue means cooperable with the rear row of burner outlets defining a path for the circulation of combustion products through said housing, said radiant units being positioned overlying the front row of burner outlets.

In testimony whereof I have hereunto subscribed my name at Nashville, Davidson County, Tennessee.
